UNITED STATES PATENT OFFICE

151,514

DESIGN FOR A FOOD CHOPPER

Frederick P. Hess and Herbert A. Wormeck, Philadelphia, Pa., assignors to The Enterprise Manufacturing Co., Philadelphia, Pa., a corporation of Pennsylvania

Application January 7, 1948, Serial No. 143,584

Term of patent 14 years

(Cl. D89—1)

To all whom it may concern:

Be it known that we, Frederick P. Hess and Herbert A. Wormeck, citizens of the United States, residing in Philadelphia, Philadelphia County, Pennsylvania, have invented a new, original, and ornamental Design for a Food Chopper, of which the following is a specification, reference being had to the accompanying drawing, forming part thereof, in which:

Fig. 1 is a view in perspective of a food chopper, showing our new design;

Fig. 2 is a top plan view of the chopper;

Fig. 3 is one side elevational view;

Fig. 4 is a front elevational view;

Fig. 5 is the other side elevational view thereof; and

Fig. 6 is an enlarged sectional view on line 6—6, Fig. 4.

We claim:

The ornamental design for a food chopper, substantially as shown.

FREDERICK P. HESS.
HERBERT A. WORMECK.
